SHOWER BATH FOR INVALIDS

Gerald K. Chapin, Catonsville, Md.

Application April 19, 1950, Serial No. 156,903

14 Claims. (Cl. 4—146)

1

This invention relates to a shower or bath for wheel chairs and is particularly useful for patients or invalids unable to take showers or baths in the customary manner.

The primary object of my invention is the provision of a waterproof shower forming enclosure adapted to be attached to wheel chairs of standard construction of such character that patients or invalids who are unable to get freely about because of muscle deficiencies, or the like, can easily get into it, can readily manipulate it, and can take a bath or shower with facility and comfort.

Another object of my invention is the provision of a shower forming enclosure which is adjustable as to height in a simple manner.

A further object resides in the provision of a firm foot rest or support to aid in getting into the enclosure and to prevent the user from toppling forward when taking a shower.

Still another object is the provision of a combined foot rest or support and compartment for storing the enclosure when not in use, which may be readily moved about with the wheel chair.

Another object is the provision of a shower enclosure having a side wall or flap which, when open, may be conveniently laid on an adjoining bed to act as a waterproof pad for the bed for the user to get onto upon leaving the enclosure and thus prevent getting the bed wet.

Other objects have to do with simplicity of construction, ready accessibility, the provision for forming a pool of water in the bottom of the enclosure, and easy drainage.

How the foregoing, together with such other objects and advantages as will hereinafter appear, are realized is illustrated in the accompanying drawings, in which—

Figure 1 is a side elevational view of a device constructed in accordance with my invention applied to a wheel chair of standard construction;

Figure 2 is a front view of Figure 1, illustrating my invention associated with a bed;

Figure 3 is an isometric view of the shown enclosure removed from the wheel chair;

Figure 4 is a fragmentary plan section taken on the line 4—4 of Figure 1;

Figure 5 is an enlarged fragmentary sectional elevational view of an adjusting and clamping device I employ;

Figure 6 is an enlarged plan section taken on the line 6—6 of Figure 5, with the clamping handle in the position it assumes during adjustment;

Figure 7 is an enlarged plan section on the line 7—7 of Figure 1;

Figure 8 is a fragmentary front elevational view showing a modification of the invention; and

2

Figure 9 is a fragmentary side elevational view of another modification of the invention.

In the drawings I have illustrated a wheel chair A of standard tubular frame construction having rear upright frame members 10, front upright frame members 11 bent rearwardly at 12 to support arm rests 13, lower connecting frame members 14, diagonal cross braces 15, and lower supports 16 for the folding foot boards 17. The main wheels 18 of the chair are provided with self-propelling hard rims 19 and the rear wheels 20 are swiveled. A seat cushion 21 and a back cushion 22 are provided.

The shower enclosure device of my invention 15 comprises in general a waterproof shower enclosure B made of waterproofed fabric, rubber, or other waterproof material; supporting framework indicated as a whole by the reference letter C; brackets D for attaching the framework C to the chair; and hooks E for detachably hanging the 20 enclosure B from the supporting framework C.

The brackets D each comprise a pair of clamping members 23 adapted to clamp around the chair, uprights 10, and a support member 24 having an upwardly extending stud 25. The support member 24 and clamping members 23 are secured together and are securely clamped in place on the chair uprights by means of screws 26. An upright rod 27 is clamped between the clamping members 23 and this rod may be used 30 for the attachment of any desired accessory.

The supporting framework C of the shower enclosure comprises a pair of upright supports each having a lower tubular member 28 fitting the stud 25 of a bracket D; an upper tubular member 29 having a forwardly extending arm 30; and an intermediate adjusting rod 31 having its lower end portion 32 fitted into the lower member 28, and its upper end portion 33 fitted into the upper member 29. The adjusting rod 31 has a 35 shouldered portion 34 which seats against the top of the lower member 28. The upper portion 33 of the adjusting rod is of oval shape in cross section, as seen in Figure 6, and the upright portion of the upper tubular frame member 29 has its sides 40 squeezed in to make it oval in cross section, as seen in Figure 6, to fit the oval rod.

With the adjusting rod and tube in the relation shown in Figure 6, the upper tubular frame member 29 can be adjusted up or down to the desired position, and when so adjusted the handle 35 connected to the adjusting rod at the shouldered portion 34 is turned until the large diameter of the adjusting rod spreads the tubular member to firmly grip it and lock the frame in adjusted 45 position. After adjustment the handle is swung

downwardly on its pivot 36 to fit snugly against the frame member 28.

The shower enclosure B is hung by means of simple hooks E from an upper support 37 preferably of rectangular shape as shown in dot and dash lines in Fig. 3. The support 37 has longitudinally extending tubes 38 secured thereto as by means of brazing for receiving the arms 39 of the members 29 and is thus held in position above the chair.

The shower enclosure B is shaped so that it will be received into and substantially fit the space formed by the back seat and arms of the chair and rise thereabove to the desired height. Toward the front, in advance of the seat, the enclosure depends or extends downwardly to a point well below the seat to form a pocket 39 for the feet of the user. In this connection it will be noted, as viewed in Figure 1, that the enclosure extends forwardly of the chair at its lower portion to form this pocket. In other words, the enclosure B is of rectangular cross section horizontally considered at its upper portion and flares forwardly at its lower portion to be of larger cross section to provide ample foot room.

Stated in another way, the shape of the enclosure is such that the occupant may sit therein with his feet depending in the pocket without subjecting the enclosure to any strain and with sufficient roominess.

In order to gain entry into the interior of the enclosure, I provide for opening one side of the enclosure, in this instance the left side 40 as viewed in Figure 2, as by means of zippers 41-42 at the edges where this side joins the front and rear walls of the enclosure. It will be noted that the zipper 41 at the rear edge extends from the top downwardly to a point 43 somewhat below the arm of the chair and that the zipper 42 at the front edge extends from the top downwardly to a point 44 somewhat below the top of the foot pocket 39. In Figure 3 I have shown the side wall or flap 40 in the act of being opened. In Figure 2 I have shown this wall or flap 40 in dot and dash lines entirely opened and extending over the arm of the chair across a bed 45 to form a waterproof pad for the bed. It is pointed out that by extending the front zipper down to the point 44 the user has only to lift his feet a small amount in getting out of the enclosure—a feature of advantage.

A shower tube and spray head indicated in dot and dash lines at 46 in Figure 2 is passed into the enclosure by means of an access opening 47, preferably provided in the side wall 40. This opening is located at a point convenient to the user and is provided with an inner flap 48 (see Figure 4) covering the opening and open at the front 49. This flap acts as a protection against water passing out through the access opening 47.

The foot pocket 39 in addition to giving ample foot room to the user also serves as a pocket for collecting a pool of water for foot bathing or for rinsing out wash cloths. A drain opening 50 is located in this pocket at a level to provide a pool of sufficient depth, and water may be led off by means of a hose 51.

In order to give support to the feet, I have provided a support in the form of a box 52 adapted to fit under the foot pocket 39 and in between the wheels of the chair when the foot boards are hinged upwardly as shown in Figure 2. This box resting on the floor gives very solid foot support which is of the utmost importance with users having muscle deficiency, such as oc-

fers in polio cases and in which cases there would be great danger from toppling forward in the absence of such foot support. In addition to making this box of the proper height to give a required foot support, I make the length and width thereof of such dimension that the enclosure B can be folded up and stored in the box. The box can be conveyed around by the wheel chair by moving the chair until the cross braces

10 15 push against the back of the box. Thus for convenience the box can be stored in the patient's room and the chair and box together can be conveniently moved to the point of use, the enclosure removed from the box, and then hooked 15 into place on the supporting framework.

To drain the pool of water, the chair is moved to engage the back of the box which permits the front of the pocket 39 to hang downwardly over the front edge of the box to lower the drain 20 opening.

In Fig. 8 I have shown a modification in which the box 52 is provided with fittings 53 positioned to ride on the upper curved surfaces 54 of the foot boards 17 to have hooked engagement there- 25 with and hold the box spaced above the floor. Since the footboards are pivoted at 16, pressure on top of the box forces the foot boards inwardly toward the sides of the box to grip and hold it firmly in place.

30 In the modification of Figure 9 I have shown a tent top 55 supported on the supporting framework C and tent sides 56 hung from this top, as by means of snap fasteners 57.

The general procedure in using my device is 35 to wheel the chair with the box 52 in place, next to a bed, as shown in Figure 2, apply the framework C, adjust it to proper height, apply the enclosure B with the openable side 40 toward the bed and in open position, it being pointed out 40 that the material of the enclosure will give to suit the adjustment, move the feet onto the box 52 to get support, move into the enclosure, close the open side, pull the shower 46 in, and then proceede with the shower. When finished the 45 side 40 is opened and laid on the bed to act as a pad and the user then leaves the chair, getting onto this pad until finished drying. Next the enclosure, after having been drained, is removed from the framework and stored in the box. The 50 framework may then be removed or left in place for subsequent use.

While I have shown the device applied to a wheel chair of tubular metal construction, it is to be understood it is equally applicable to other 55 types of chairs, as, for example, wooden chairs.

I claim:

1. Apparatus for the shower bathing of invalids comprising a chair having a plurality of 60 wheels providing for mobility of the chair; a shower enclosure device comprising supporting brackets secured to the chair; framework detachably mounted on said brackets; and a waterproof enclosure hung from said framework having an openable side to give entry into the enclosure.

2. Apparatus for the shower bathing of invalids comprising a chair having a plurality of 65 wheels providing for mobility of the chair; a shower enclosure device comprising supporting brackets secured to the chair; framework detachably mounted on said brackets; and a waterproof enclosure hung from said framework, said enclosure having an openable side to give entry into said enclosure, a foot pocket at the lower 70 75

portion of said enclosure and a drain opening in said foot pocket.

3. Apparatus for the shower bathing of invalids comprising a chair having a plurality of wheels providing for mobility of the chair; a shower enclosure device comprising supporting brackets secured to the chair; framework detachably mounted on said brackets; and a waterproof enclosure hung from said framework, said enclosure having an openable side to give entry into said enclosure, a foot pocket at the lower portion of said enclosure and a drain opening in said foot pocket, said drain opening being located in said pocket at a point above the bottom thereof to enable a pool of water to be formed in said pocket.

4. Apparatus for the shower bathing of invalids comprising a chair having a plurality of wheels providing for mobility of the chair; a shower enclosure device comprising supporting brackets clamped to rear supports of the chair, upright supporting members secured to said brackets, an upper supporting frame carried by said upright supporting members, a waterproof enclosure, hooks for hanging said enclosure from said frame, said enclosure having a rear portion extending downwardly from said frame to the seat of said chair and having a front portion extending below the level of said seat to form a foot pocket, and a drain opening in said pocket.

5. Apparatus for the shower bathing of invalids comprising a chair having a plurality of wheels providing for mobility of the chair; a shower enclosure device comprising brackets clamped to rear supports of the chair, upright supporting members secured to said brackets, an upper supporting frame of rectangular form carried by said upright supporting members, a waterproof enclosure, and hooks for hanging said enclosure from said frame, said enclosure being substantially of rectangular form in horizontal cross section in its upper portion and flaring to larger cross section in its lower portion to form a front foot pocket.

6. Apparatus for the shower bathing of invalids comprising a chair having a plurality of wheels providing for mobility of the chair; a shower enclosure device comprising brackets clamped to rear supports of the chair, upright adjustable supporting members secured to said brackets, upper support structure carried by said upright supporting members, a waterproof enclosure, hooks engaging said upper support structure and said waterproof enclosure to hang the enclosure from said support structure, said waterproof enclosure having an openable side, and means for opening and closing said side.

7. Apparatus for the shower bathing of invalids comprising a chair having a plurality of wheels providing for mobility of the chair; a shower enclosure device comprising a waterproof enclosure having an openable side to give entry thereto; supporting framework for said waterproof enclosure; and brackets secured to said chair for carrying said framework; said supporting framework including upright means for adjusting its height, and said adjusting means comprising lower tubes secured in said brackets, upper tubular frame members of substantially oval form in cross section, adjusting rods mounted in said lower tubes for rotation and having upper portions of substantially oval form in cross section fitting said upper tubular members in telescopic relation, and means for turning said

rods to secure the frame members in adjusted position.

8. Apparatus for the shower bathing of invalids comprising a chair having a plurality of wheels providing for mobility of the chair; a shower enclosure device comprising brackets clamped to rear supports of the chair, upright supporting members secured to said brackets, an upper supporting frame carried by said upright supporting members, a waterproof enclosure, hooks for hanging said enclosure from said frame, said enclosure having a rear portion extending downwardly from said frame to the seat of said chair, a front portion extending below the level of said seat to form a foot pocket, an openable side, and zipper means for opening and closing said side, said zipper means including a rear zipper extending downwardly from the top of said enclosure to the seat of the chair and a front zipper extending from the top of said enclosure to said foot pocket.

9. Apparatus for the shower bathing of invalids comprising a chair having a plurality of wheels providing for mobility of the chair; a shower enclosure device comprising brackets secured to rear supports of the chair, upright supporting members secured to said brackets, an upper supporting frame carried by said upright supporting members, a waterproof enclosure, and hooks for hanging said enclosure from said frame, said waterproof enclosure having an openable side adapted when open to be laid over a bed to serve as a pad when said chair is placed adjacent said bed.

10. Apparatus for the shower bathing of invalids comprising a chair having a plurality of wheels providing for mobility of the chair; a shower enclosure device comprising supporting brackets secured to the chair; framework detachably mounted on said brackets; a waterproof enclosure hung from said framework, an openable side for said enclosure to give entry into the enclosure, an access opening in said enclosure for the insertion of a shower device, and a flap covering said access opening.

11. Apparatus for the shower bathing of invalids comprising a chair having a plurality of wheels providing for mobility of the chair; a shower enclosure device comprising supporting brackets secured to the chair; framework detachably mounted on said brackets; a waterproof enclosure hung from said framework, said enclosure having an openable side to give entry into said enclosure; a foot pocket at the lower portion of said enclosure; and a foot support located under said pocket.

12. Apparatus for the shower bathing of invalids comprising a chair having a plurality of wheels providing for mobility of the chair; a shower enclosure device comprising supporting brackets secured to the chair; framework detachably mounted on said brackets; a waterproof enclosure hung from said framework, said enclosure having an openable side to give entry into said enclosure; a foot pocket at the lower portion of said enclosure; and a foot support carried by the wheel chair and located under said pocket.

13. In combination with a wheel chair having the usual frame structure, and pivoted foot boards; a shower enclosure device comprising brackets secured to the frame structure of the wheel chair; framework detachably mounted on said brackets; a waterproof enclosure hung from said framework having an openable side to give

entry into the enclosure; a foot pocket at the lower portion of said enclosure; and a foot support under said pocket, said foot support being carried by the wheel chair foot boards.

14. Apparatus for the shower bathing of invalids comprising a chair having a plurality of wheels providing for mobility of the chair; a shower enclosure device comprising supporting brackets secured to the chair; framework detachably mounted on said brackets; a waterproof enclosure hung from said framework, said enclosure having an openable side to give entry into said enclosure; a foot pocket at the upper portion of said enclosure; and a foot support located under said pocket in the form of a box proportioned to store said waterproof enclosure.

GERALD K. CHAPIN.
